UNITED STATES PATENT OFFICE.

CLARENCE E. LOMAX, OF CHICAGO, ILLINOIS, ASSIGNOR TO AUTOMATIC ELECTRIC COMPANY, OF CHICAGO, ILLINOIS, A CORPORATION OF ILLINOIS.

AUTOMATIC TELEPHONE SYSTEM.

Application filed April 19, 1920, Serial No. 374,886. Renewed April 11, 1924.

To all whom it may concern:

Be it known that I, CLARENCE E. LOMAX, a citizen of the United States of America, and a resident of Chicago, Cook County, 5 and State of Illinois, have invented certain new and useful Improvements in Automatic Telephone Systems, of which the following is a specification.

My invention relates in general to automatic telephone systems, but more especially to private automatic systems or exchanges for use in factories, mercantile establishments, etc.; and the object of the invention may be stated to be the provision of a private 10 automatic exchange, and suitable interconnecting trunk circuits therefor, which is adapted for use as part of a large manual system.

Private automatic systems of the above 20 general character have come into wide use, not only in cities having full automatic telephone systems, but recently also in cities having manual systems. A demand has arisen therefore for a more suitable trunk 25 circuit for interconnecting a manual main exchange with an automatic private branch exchange and it is to meet this need that I have devised the improved trunk circuit which with the associated equipment at the 30 main and branch exchange ends thereof forms the subject matter of this application.

In the drawings, comprising Figs. 1, 2, and 3, I have shown by means of the usual circuit diagrams a trunk circuit embodying my 35 invention which extends from the jack J' in a manual exchange, Fig. 1, to a private automatic exchange, certain essential parts of which are shown in Figs. 2 and 3. At the latter point the trunk line extends 40 through an attendant operator's position (Fig. 2) where certain relay equipment, lamp signals, etc., are provided, and terminates in an automatic connector switch which is indicated by the reference character 45 H, Fig. 3. The connector H when used as shown herein is usually called an incoming connector and is one of a plurality of similar connectors in which the main to branch exchange trunk lines terminate. These connectors are ordinary vertical and rotary 50 switches of the Strowger type and have access to the local lines in the branch exchange, one of which is the line extending to station A'.

55 In order to handle outgoing calls from the

local lines each line is provided with an individual line or trunk selecting switch, the line switch associated with the line of station A' being indicated in Fig. 3 by reference character C. All of these line switches 60 may have common access to a group of local connectors (not shown) which have access to the local lines the same as do the incoming connectors like the connector H. The local connectors are preferably of the type 65 in which provision is made for an automatic rotary movement on two of the levels, in order that access may be had to the trunk lines connecting with the main exchange, and also to a group of trunk lines extending 70 to the attendant operator's position. The multiple bank contacts 150, 151, and 152 in the upper left hand corner of Fig. 3 are located in the bank of a local connector and are multipled to similar contacts in other 75 similar connectors. The local switching mechanism forms no part of the invention, but since on this account no local connector is shown, reference is made to the U. S. patent to Martin, No. 1,291,990, which shows 80 how a connector may be given an automatic rotary or trunk selecting movement on a certain level.

Having indicated the scope of my invention in general terms, I will now proceed to 85 explain the operation of the particular embodiment thereof which I have shown in the drawings. For this purpose it will be assumed that the subscriber at station A, Fig. 1, desires to obtain connection with the 90 subscriber at station A', Fig. 3. When the receiver is removed at station A, a circuit is completed for the line relay 2, and this relay is energized to light the line lamp L in the usual manner. Upon perceiving the 95 signal, the operator will respond by inserting the answering plug of an idle cord circuit, cord circuit O for example, in the jack J. By this operation a circuit is completed over the sleeve of the jack which includes the cut-off relay 3 and the supervisory lamp L' in series. The cut-off relay is energized and cuts off the line relay 2, thereby extinguishing the line lamp L; but since the receiver is off the hook at the calling 100 station the supervisory relay 4 in the cord circuit will energize at once and the lamp L' will be shunted out and will not be lighted.

105 The operator will now throw the key K 110

to listening position and will ascertain the number of the station with which the calling party desires a connection. This being the station A' in the branch exchange, whose number may be assumed to be No. 67, the operator will next test the outgoing trunks extending to the branch exchange with the tip of her calling plug in order to select an idle trunk. Assuming that the trunk line 10 shown is the trunk selected, the operator will insert the calling plug in jack J', whereupon a circuit will be established over the sleeve of the jack which includes supervisory lamp L² and the cut-off relay 12. 15 Relay 12 at once energizes and at its armature 16 closes the following circuit for the line relay 101 of the connector H; ground at G², winding of relay 13, lower right hand winding of repeating coil R, armature 16 and 20 its working contact, contact springs of key K', conductor 81, contact springs of key K², resting contact of armature 39 and the said armature, contact spring 40 of key K³ and its resting contact, conductor 99, armature 25 115 and its resting contact, normally closed contact springs controlled by armature 128 of relay 106, and the winding of the line relay 101 to battery. Upon the closure of the above circuit relay 13 and the line 30 relay of the connector H are energized in series, the former being effective at this time to open at its armature 18 a shunt circuit which was closed around the condenser C by the operation of relay 12. As a result, 35 no current will flow through the supervisory relay 5 and the supervisory lamp L² will be lighted.

At the connector H, the line relay 101, 40 upon energizing, closes a circuit for the slow acting release relay 102 as follows: ground at G³, armature 116 and its working contact, off normal spring 163 and its resting contact, and the winding of relay 102 to battery. Upon energizing, relay 102 prepares a circuit for the vertical magnet 109 45 at its armature 119, disconnects the cut-off relay 100 at the resting contact of its armature 117, and at the working contact of the same armature connects ground G⁴ to the conductor 95, which corresponds to the usual release trunk conductor. By the grounding of conductor 95 a ground potential is placed 50 on test contact 151 and its multiples in the banks of the local connectors thereby making the trunk line busy to outgoing calls from the branch exchange. It will be observed also that conductor 95 extends back to the attendant operator's position, Fig. 2, 55 where it supplies current to the busy lamp L⁶, maintaining this lamp lighted as long as the trunk line is in use. There is another circuit extending from the connector H back to the lamp L⁷ at the attendant's position which extends as follows: grounded 60 conductor 95, armature 114 of relay 100 and 65

its resting contact, resting contact of armature 127 and the said armature, off normal spring 161 and its resting contact, conductor 98, resting contact of armature 37 and the said armature, and the lamp L⁷ to battery. 70 Lamp L⁷ is one of the supervisory lamps provided to give the attendant operator complete supervision. In its lighted condition lamp L⁷ indicates that the connector H has been taken for use but has not been operated. 75

The operator at the main exchange will now operate the calling device key K' which is associated with the trunk line in use, thereby inserting her calling device S in the circuit of the line relay 101 of the connector H. The dial of the calling device being now operated in accordance with the first digit 6 of the desired number in the branch exchange, a series of six interruptions is produced in the line relay circuit, and the line relay is accordingly deenergized momentarily a like number of times, at each deenergization transmitting an impulse of current to the vertical magnet as follows: ground at G³, armature 116 and its resting contact, resting contact of armature 125 and the said armature, winding of slow acting series relay 104, resting contact of armature 132 and the said armature, contact springs controlled by armature 122, working contact of armature 119 and the said armature, and the winding of the vertical magnet 109 to battery. Responsive to impulses received over the above circuit the vertical magnet operates to raise the switch shaft step by step until the wipers 140-142, inclusive, stand opposite the sixth level of bank contacts. At the first upward movement of the shaft the off normal springs 161-164 are shifted, and at the resting contact of spring 163 the original energizing circuit of the slow acting relay 102 is broken. The slow acting series relay 104 having energized in series with the vertical magnet, however, a new circuit has been established as follows: ground at G³, armature 116 and its working contact, off normal spring 163 and its working contact, armature 124 and its left hand working contact, and the winding of relay 102 to battery. 100 Relay 102 receives current impulses over the above circuit to maintain it energized during the vertical movement. Relay 104 also remains energized during the vertical movement, being in series with the vertical magnet, but after the last vertical impulse has been delivered relay 104 deenergizes and breaks the circuit of relay 102. At the same time a circuit for slow acting relay 103 is closed as follows: ground at G³, armature 116 and its working contact, off normal spring 163 and its working contact, armature 124, and its resting contact, and the winding of relay 103 to battery. 110 Relay 103 is energized before the slow act- 115

ing relay 102 has had time to deenergize and at its armature 120 closes a branch path over which ground G^4 may be maintained in connection with conductor 95. Relay 103 5 also connects up the rotary magnet 110 at armature 122 and disconnects the vertical magnet 109. Some other circuit changes produced by the shifting of the off normal springs may now be noticed. The circuit of 10 the release magnet 112 is prepared at off normal spring 164, at off normal spring 162 the cut off relay 100 is disconnected, and by the shifting of off normal spring 161 from its resting to its working contact the circuit 15 of the switch supervisory lamp L^7 , which extends over conductor 98, is broken and a circuit is completed which extends over conductor 96 to the regular supervisory lamp L^5 . Lamp L^7 is thus extinguished and lamp 20 L^5 is lighted. This condition of the lamps indicates to the attendant that although the connector has been operated the called party has not answered.

The connector H is now ready to respond 25 to the calling of the final digit, which is the digit 7. When the dial is operated in accordance with this digit a series of seven interruptions is produced in the line relay circuit causing this relay to deenergize as 30 before described. Now, however, since relay 103 is energized, current impulses are transmitted to the rotary magnet 110. The circuit is the same as was described in the case of the vertical magnet except that it is 35 switched over to the rotary magnet at armature 122 of relay 103. By the operation of the rotary magnet 110 the shaft of the switch is rotated step by step until the wipers are finally brought to rest in engagement 40 with the bank contact in which is terminated the line of station A', these bank contacts being indicated in the drawing by reference characters 143-145, inclusive. The slow acting relay 104 is energized as before, 45 remaining in operated position during the rotation of the switch, and at the back contact of its armature 124 breaks the normal energizing circuit of relay 103, immediately closing, however, another circuit for the 50 same relay at the right hand working contact of the same armature. Relay 103, therefore remains in operated position. It will be seen also that the circuit of slow acting relay 102 is closed at the left hand working contact of armature 124 and this relay is 55 also energized and maintained in operated position while the switch is rotating. The circuit changes brought about at armatures 117 and 119 are in this instance of no special consequence, the object of energizing relay 102 again being the preparation of a busy release circuit at armature 118. This is brought into use as follows: When the 60 slow acting relay 104 falls back at the end of the rotation of the switch, the circuits of

relays 102 and 103 are both broken by armature 124, the circuit of the latter relay being immediately reestablished at the back contact of this armature. Assuming, now that the line of station A' is busy when called, 70 there will be a ground potential upon the test contact 144, and when relay 104 deenergizes, a circuit is closed through the release magnet 112 as follows: ground on test contact 144, test wiper 141, armature 123 75 and its resting contact, armature 118 and its working contact (slow acting relay 102 remaining in operated position for an instant), lower winding of busy test relay 105, off normal springs 164, and the winding of 80 the release magnet 112 to battery. By the operation of release magnet 112 the switch is restored to normal position. When the switch shaft becomes completely restored the 85 off normal springs are shifted back to their original condition and the release magnet circuit is broken. The busy test relay 105 is energized in series with the release magnet and establishes a locking circuit for itself 90 which for all practical purposes may be considered as extending from the grounded conductor 95 by way of the upper high resistance winding of said relay to battery. The locking arrangement shown, however, 95 may be used to save a contact spring, the upper winding of the relay 105 being switched on to the magnet circuit which extends through relay 104 and either magnet 110 or 109 (the latter as soon as the switch becomes completely restored) to battery. 100 Thus the magnet circuit is broken and a locking circuit is established also, with a minimum of contact springs. In its energized position relay 105 connects a lead from the busy signaling machine Q to the lower 105 heavy talking conductor, thereby giving the operator at the distant main exchange an audible busy signal.

Having explained the operations which 110 take place when a busy line is called, we will now proceed with the establishment of the connection under consideration, it being assumed that the line of station A' was idle when called. The switch wipers having 115 been brought to rest in engagement with bank contacts 143-145, inclusive, as previously described, when the slow acting relay 104 deenergizes at the end of the rotation of the switch the circuit of the release magnet will not be closed because the test wiper 141 will find no ground potential on test contact 144. Nothing happens therefore until relay 102 deenergizes which occurs an instant later. A circuit is then completed which includes the switching relay 120 108 and the switching relay 146 of line switch C in series, extending as follows: grounded conductor 95, winding of relay 108, normally closed contact springs controlled by armature 132, resting contact of 125 130

armature 118 and the said armature, resting contact of armature 123 and the said armature, wiper 141, test contact 144, winding of relay 146 and the winding of the stepping magnet 147 to battery. By the closure of the above circuit the switching relay 146 is energized and operates to disconnect the conductors of the called line from their normal battery and ground connections. Relay 146 does not completely operate its armatures due to the fact that the line relay of the line switch has not been energized, and the line conductors are not connected through to the wipers of the line switch. At the connector H relay 108 is energized in series with relay 146 and at its armature 132 breaks the rotary magnet circuit, at the same time connecting the lead from the rotary magnet to its upper terminal in place of the conductor extending to the test wiper 141. This arrangement is another expedient used to economize in contact springs, and accomplishes the object intended which is to open the operating circuit of the rotary magnet and establish a locking circuit for relay 108. At its armature 133 relay 108 connects direct ground to the test wiper 141, thus rendering test contact 144 and its multiples busy to other calls, and at its armature 134 relay 108 connects up the lower line wiper 142. It will be observed that the lower winding of the ring cut off relay 107 is connected to battery by the spring combination controlled by armature 132, and it follows therefore that the usual ringing circuit has now been established. Ringing current from generator Gen is projected out over the called line in the customary manner to operate the bridged ringer at station A', the return path for the ringing current including the upper heavy line conductor, the lower winding of the ring cut-off relay, the rotary magnet 110, and the grounded branch exchange battery. When the called subscriber responds by removing his receiver the ring cut-off relay 107 is operated in the usual manner and establishes a locking circuit for itself at its armature 130, opens the ringing circuit at armatures 129 and 131, and at the working contacts of these same armatures finally completes the talking circuit through to the called line. Talking current is supplied to the transmitter at the called station through the windings of the double wound back bridge relay 106 which energizes immediately after the ring cut-off relay pulls up and remains energized as long as the receiver remains off the hook. At its armature 127 relay 106 disconnects ground from the off normal spring 161 and thus extinguishes the supervisory lamp L⁵ at the attendant's position, indicating to the attendant operator the fact that the attempted connection has been successful.

Supervision is also given to the operator at the main exchange and this operation will now be explained. When the calling of the final digit was completed the operator of course restored the calling device key K' and the relay 13 is thereby again inserted in the line relay circuit and is energized thereover. The supervisory lamp L² which was temporarily extinguished during the dialing operation, is again lighted. Now when the relay 106 of the connector pulls up on the response of the called subscriber the line relay circuit extending from ground G² and through the winding of relay 13 is broken at armature 128 of relay 106 and the line relay 101 is energized by a local circuit in the connector. Relay 13 is accordingly deenergized and extinguishes the lamp L², this result being accomplished by the short-circuiting of the condenser C which permits the supervisory relay 5 to energize. It will be seen then that the main exchange operator is given the standard supervision.

When the conversation is finished both subscribers will hang up their receivers. The replacement of the receiver at station A causes the lighting of the supervisory lamp L' in the usual manner, while the replacement of the receiver at station A' causes the lighting of supervisory lamp L² through the falling back of relay 106 and the consequent energization of relay 13. Upon observing the lighted supervisory lamps the operator will know that the conversation is over with and she will accordingly pull down the connection. The release of the connector H is brought about following the deenergization of the line relay 101 which falls back when the lower line conductor is opened at armature 16 of relay 12. Relay 101 breaks the circuit of slow acting relay 103 which, upon deenergizing, closes the release magnet circuit at the resting contact of armature 120 and the switch is restored to normal. When this occurs the busy lamp L⁶ at the attendant's position and the supervisory lamp L⁵ which was lighted when the called party hung up, are both extinguished, whereupon all the equipment in use will have been restored and made ready for use in another call.

There is a certain class of main to branch exchange calls in which the main exchange subscribers simply desire connection with the company served by the branch exchange, not being familiar with its organization and being uncertain as to the department or individual who should handle the business in hand. These general calls are referred to the attendant operator at the branch exchange and are by her routed to their proper destinations. The process of establishing a connection of this class will now be explained. For this purpose it will be as-

sumed that the subscriber at station A desires to obtain connection with Blank and Co., we will say, this being the company having the branch exchange equipment shown. The connection may be handled by the main exchange operator substantially as before described, the cord circuit O being used to connect the calling line with an idle trunk to the branch exchange which we will assume to be the trunk terminating in jack J'. When the plug is inserted in jack J' the line relay circuit extending to connector H is completed, relays 101 and 102 of the connector are energized, and the busy 15 and switch supervisory lamps L⁶ and L⁷ at the attendant's position are lighted, all as before explained. Since the call is to be turned over to the attendant at the branch, the main exchange operator does not now 20 operate her calling device, she doesn't know what number to call anyway,—but instead she will throw her key K to ringing position momentarily. This operates the ring down relay 32 which is bridged across the 25 trunk at the attendant's position, and this relay locks itself at its armature 35, the circuit being readily traceable over conductor 98 to the grounded off-normal spring 161 at the connector. Relay 32 also breaks 30 the circuit of lamp L⁷ at armature 37 and closes the circuit of lamp L⁴ at armature 36. Lamp L⁴ is the call signal and indicates to the attendant operator that she is being 35 called from the main exchange.

35 The attendant operator answers by throwing her listening and calling device key K³, producing numerous circuit changes which will be explained. To begin with, by the separation of contact springs 42 the locking 40 circuit of relay 32 is broken, this relay being deenergized and the call signal lamp L⁴ being extinguished. By the closure of contact springs 43 the grounded conductor 97 is connected to relay 33 which energizes 45 and establishes a locking circuit for itself at its armature 38. In addition, at its armature 39, relay 33 breaks the continuity of the lower heavy talking conductor and divides this conductor into two sections which 50 are, however, inductively connected by the condenser C'. At the same time the impedance coil 34 is connected to the section extending in the direction of the connector H, the effect being to substitute coil 34 for 55 relay 13 in the line relay circuit. Relay 13 therefore deenergizes and short circuits condenser C by which operation the supervisory lamp L² is extinguished and the main exchange operator is advised that the 60 attendant has answered. As a further result of the operation of key K³ the attendant's calling device is inserted in the line relay circuit extending to the connector H, and this circuit will now be traced: ground 65 at G⁶ winding of coil 34, working contact

of armature 39 and the said armature, contact spring 40 and its working contact, conductor 47, impulse springs of calling device S', contact springs of releasing key K⁴, conductor 48, and working contact of contact spring 41 and the said spring to conductor 99, whence the circuit continues as previously traced to the connector H and through the line relay 101 to battery. A circuit in multiple with the above for the line relay 101 may be traced from ground G⁶, through the winding of coil 34, working contact of spring 46 of key K³ and the said spring, to conductor 47 and thence over the previously traced circuit to the line relay 101. This circuit has no function at the present time. However, should the attendant operator be called upon to set up a connection to the main exchange for a branch exchange subscriber, the line relay 80 70 75 85 90 95 100 105 110 115 120 125 130 135 140 signal. When the called subscriber answers relay 106 at the connector removes ground from the conductor 97 and breaks the locking circuit of relay 33 which thereupon de-energizes and restores the line relay circuit over the lower heavy trunk conductor to its original condition. This places the supervisory lamp L^2 under the control of the called party, and we have the same conditions existing as when the connection was established by the main exchange operator herself. The various supervisory lamps at the attendant's position of course operate the same no matter which operator sets up the connection.

If the attendant operator at the branch exchange wishes to signal the main exchange operator for the purpose of obtaining connection with a main exchange subscriber she may do so in the following manner: Assuming that the trunk line shown in the drawings is not in use, as indicated by the unlighted condition of busy lamp L^6 , the attendant operator will actuate key K^2 momentarily. By this operation a circuit is closed for relay 13 at the main exchange as follows: ground at G^2 , winding of relay 13, upper right hand winding of the repeating coil R , conductor 30, contacts of key K^2 , and the resistance 53 to battery. Upon energizing, relay 13 locks itself at its armature 20, and at its armature 19 closes the circuit of the line lamp L^3 . The line lamp is therefore lighted and notifies the main exchange operator that a call has been received over the trunk line associated therewith. When the operator plugs into the jack J' to answer the call the cut-off relay 12 is energized and operates to break the locking circuit of relay 13 and extinguishes the line lamp L^3 . The connection can then be extended to any main exchange subscriber in the usual manner.

Since the attendant operator can call in both directions over the trunk lines passing through her position, she can set up connections for the branch exchange subscribers if they should desire her to do so. Important officials of the company may at times be too busy to bother with obtaining their own through main exchange connections, which necessarily involve some little waste of time, and will prefer to have these connections obtained for them by the attendant. Suppose the party at station A' desires a main exchange connection and has no time to bother with it himself. He will remove his receiver, whereupon his line will be extended in the well known manner to an idle local connector through the medium of the individual line switch C . The subscriber can now operate his calling device and by raising the connector to the proper trunk selecting or rotary level can obtain

connection with a local trunk line leading 65 to the attendant operator's position. When the attendant answers she is given the necessary data on the desired connection and the branch exchange subscriber then hangs up his receiver. The attendant will now proceed 70 to call the desired party in the main exchange as before explained and after obtaining the connection she will call back on the trunk line in the reverse direction to connect with the branch exchange subscriber 75 who initiated the call.

The branch exchange subscribers may, however, call the main exchange direct if they so desire. The operation is initiated by removing the receiver, whereupon (if station A' is calling) the line switch C operates to extend the line of station A' to a local connector, as before stated. By suitable operation of the calling device the connector is now raised to the level in which the main branch exchange trunk lines are terminated, and a further operation of the connector results in the automatic selection 85 of an idle one of these trunks. Assuming that the trunk line shown is the trunk 90 selected, the connector wipers will have established connection with the bank contacts 150, 151, and 152 either directly or through a multiple thereof, depending on the switch 95 in which these contacts are located; and the private wiper of the connector will place a ground on the test contact 151. By this means a circuit is closed for relay 100 of the connector H which, upon energizing, disconnects the incoming trunk conductors 100 from the connector at its armatures 113 and 115, and at its armature 114 disconnects the now grounded conductor 95 from the off-normal spring 161 of the connector. This 105 prevents the lighting of the switch supervisory lamp L^7 at the attendant's position, although the busy lamp L^6 is lighted as usual. The connection to the trunk having been completed, the main exchange operator 110 is signalled the same way as was described in the case where she was being called by the attendant, except that battery is connected to the upper trunk conductor by the local connector instead of by the operator. This 115 will be readily understood when it is recalled that the upper wiper of an automatic connector is connected to battery after the connector has been operated, in certain types of connectors through a winding of the back bridge relay and in other types 120 through a winding of the ring cut off relay. In either case battery will be connected to the upper trunk line conductor and the relay 13 at the main exchange will be energized to signal the main exchange operator, after 125 which the connection may be completed in the ordinary manner.

Having described my invention what I

consider to be new and desire to have protected by Letters Patent will be pointed out in the appended claims.

What I claim is:

- 5 1. In a telephone system, a manual main exchange and an automatic branch exchange, an attendant operator's position at the branch exchange, continuous two way trunk lines passing through said operator's position 10 and connecting said exchanges, and means including said trunk lines for completing interexchange calls originating in either exchange.
2. In a telephone system, a manual main exchange and an automatic branch exchange, an attendant operator's position at the branch exchange, a continuous trunk line passing through said operator's position and connecting said exchanges, and means where- 20 by operators in the main exchange and calling subscribers in the branch exchange can complete interexchange connections over said trunk line.
3. In a telephone system, a manual main exchange and an automatic branch exchange, an attendant operator's position at the branch exchange, a continuous trunk line passing through said operator's position and connecting said exchanges, means including 30 said trunk line and an automatic switch at the branch exchange whereby a main exchange operator can complete an interexchange connection, and means including another automatic switch at the branch exchange whereby a branch exchange subscriber can signal the main exchange operator over said trunk line.
4. In a telephone system, a manual main exchange and an automatic branch exchange, 40 an attendant operator's position at the branch exchange, a continuous trunk line passing through said operator's position and connecting said exchanges, means whereby either a main exchange operator or a calling branch exchange subscriber can signal the attendant operator, and means including said trunk line whereby said attendant operator can complete interexchange connections originating in either exchange.
5. In a telephone system, a manual main exchange, and an automatic branch exchange, an attendant operator's position at the branch exchange, a continuous trunk line connecting said exchanges and extending 55 through said attendant's position, means for establishing main to branch and branch to main exchange connections over said trunk line independent of the attendant operator, means for signalling the attendant from one end of said trunk line when her assistance is desired, and means whereby the attendant can answer when signalled and extend a connection over said trunk line in one direction when requested.
6. In a telephone system, a manual main exchange and an automatic branch exchange, an attendant operator's position at the branch exchange, a continuous trunk line connecting said exchanges and extending through said attendant's position, means for establishing main to branch and branch to main exchange connections over said trunk line independent of the attendant operator, a signal at the attendant's position for indicating the idle or busy condition of said trunk line, and means whereby the attendant can connect with said trunk line and call in either direction thereover when the trunk line is not in use. 65
7. In a telephone system, a manual main exchange and an automatic branch exchange, an attendant operator's position at the branch exchange, continuous two way trunk lines passing through said operator's position and connecting said exchanges, means 80 including said trunk lines for completing interexchange calls originating in either exchange, and signals at the attendant's position for enabling the attendant to supervise all calls originating in the main exchange. 90
8. In a telephone system, a manual main exchange and an automatic branch exchange, an attendant operator's position at the branch exchange, continuous two way trunk lines passing through said operator's position 95 and connecting said exchanges, means including said trunk lines for completing interexchange calls originating in either exchange, and busy signals for said trunk lines for advising the attendant operator when the 100 trunk lines are in use.
9. In a telephone system, a manual main exchange and an automatic branch exchange, an attendant operator's position at the branch exchange, continuous two way trunk lines passing through said operator's position and connecting said exchanges, means including said trunk lines for completing interexchange calls originating in either exchange, a busy signal and a supervisory signal for each trunk line at the attendant's position, means for actuating the busy signals whenever the trunk lines are 105 in use, and means for suitably controlling the supervisory signals to give the attendant 110 answering and disconnect supervision over calls originating in the main exchange. 115
10. In a telephone system, a manual main exchange and an automatic branch exchange, and an attendant operator's position at the branch exchange, a continuous inter-ex- 120 change trunk line passing through the attendant's position and terminating in an automatic switch in the branch exchange, means for establishing main to branch ex- change connections through the medium of said trunk line and switch, and a signal at the attendant's position controlled by said 125

switch when the trunk line is in use for advising the operator as to whether or not the said switch has been operated.

11. In a telephone system, a manual main exchange and an automatic branch exchange, an attendant operator's position at the branch exchange, a continuous inter-exchange trunk line passing through the attendant's position and terminating in an automatic switch in the branch exchange, means for establishing main to branch exchange connections through the medium of said trunk line and switch, a signal for giving the attendant answering and disconnect supervision over such connections, and a second signal for giving the attendant direct supervision over said switch to advise her of its normal or off normal condition.

12. In a telephone system, a manual main exchange and an automatic branch exchange, an attendant operator's position at the branch exchange, a trunk line coming from the main exchange and extending through the attendant's position to an automatic switch, means including said trunk line and switch whereby an operator in the main exchange can extend a connection to a subscriber's line in the branch exchange, means whereby the main exchange operator can signal the attendant operator if she so desires, and a supervisory signal controlled in one case by the response of the called subscriber and in the other case by the response of the attendant.

13. In a telephone system, a main exchange and a branch exchange, a trunk line connecting said exchanges, operators at both exchanges cooperating to complete main to branch exchange connections, means for giving the main exchange operator answering supervision when the branch operator comes in on the trunk to assist in setting up a connection, means whereby the branch operator after she has completed the connection can leave the trunk without giving the main exchange operator a disconnect signal, means for giving the branch operator answering supervision upon the response of the called subscriber, and means for giving both operators disconnect supervision when the called subscriber hangs up his receiver.

14. In a telephone system, a manual main exchange and an automatic branch exchange, a trunk line connecting said exchanges and terminating in an automatic switch in the branch exchange, operators at both exchanges cooperating to establish main to branch exchange connections, means for signalling the branch operator over said trunk line when a connection is wanted, means for giving the main exchange operator answering supervision when the branch operator comes in on the trunk, means whereby the branch operator can operate said switch to complete the desired connection, means

whereby the branch operator can leave the trunk before the called party answers without giving the main exchange operator a disconnect signal, means for giving the branch operator answering supervision when the called party answers, and means for giving both operators disconnect supervision when the called party hangs up his receiver.

15. In a telephone system, a manual main exchange and an automatic branch exchange, an attendant operator's position at the branch exchange, a trunk line coming from the main exchange and extending through the attendant's position to an automatic switch, means whereby a main exchange operator can signal the attendant operator when a branch exchange connection is wanted, a supervisory signal controlled by the response of the attendant to notify the main exchange operator thereof, means whereby the attendant operator can control said switch to complete the desired connection, and means whereby the attendant can disconnect herself from the trunk line before the called subscriber answers without affecting said supervisory signal.

16. In a telephone system, a manual main exchange and an automatic branch exchange, an attendant operator's position at the branch exchange, a trunk line coming from the main exchange and extending through the attendant's position to an automatic switch, means whereby a main exchange operator can signal the attendant operator when a branch exchange connection is wanted, a supervisory signal controlled by the response of the attendant to notify the main exchange operator thereof, means whereby the attendant operator can control said switch to complete the desired connection, means whereby the attendant can disconnect herself from the trunk line before the called subscriber answers without affecting said supervisory signal, a supervisory signal for the attendant operator, and means for controlling said second signal when the called subscriber answers.

17. In a telephone system, a manual main exchange and an automatic branch exchange, an attendant operator's position at the branch exchange, a trunk line coming from the main exchange and extending through the attendant's position to an automatic switch, means whereby a main exchange operator can signal the attendant operator when a branch exchange connection is wanted, a supervisory signal controlled by the response of the attendant to notify the main exchange operator thereof, means whereby the attendant operator can control said switch to complete the desired connection, means whereby the attendant can disconnect herself from the trunk line before

the called subscriber answers without affecting said supervisory signal, a supervisory signal for the attendant operator, means for controlling said second signal when the 5 called subscriber answers, and means for controlling both signals at the same time when the called subscriber hangs up his receiver.

18. In a telephone system, a two way 10 trunk line extending from a first exchange to a second exchange, call and supervisory signals at the first exchange, a relay for controlling both signals, means for controlling said relay over one conductor of said 15 trunk line independent of the other to control said call signal on incoming calls, and means for controlling said relay over the other conductor of said trunk line independent of the first to control said supervisory signal on outgoing calls.

19. In a telephone system, a two way 20 trunk line connecting two exchanges, a repeating coil in said trunk at one of said exchanges, a relay connected from the middle 25 point of the outgoing side of said repeating coil to ground, means for establishing a circuit for said relay including only one talking conductor of said trunk line and ground return when calls are extended in 30 one direction, and means for establishing another circuit for said relay including the other conductor of said trunk line and ground return when calls are extended in the other direction.

35 20. In a telephone system, a two way trunk line connecting two exchanges, a repeating coil in said trunk at one of said exchanges, a relay connected from the middle point of the outgoing side of said repeating coil to ground, means for establishing a 40 circuit for said relay including only one talking conductor of said trunk line and ground return when calls are extended in one direction, means for establishing another circuit for said relay including the other conductor of said trunk line and ground return when calls are extended in the other direction, call and supervisory signals, means for controlling said relay over one 45 of its circuits to control said call signal, and means for controlling said relay over the other of its circuits to control said supervisory signal.

50 21. In a telephone system, a manual main exchange and an automatic branch exchange, an attendant operator's position at the branch exchange, a trunk line coming from the main exchange and extending through the attendant's position to an automatic 55 switch at the branch exchange, means whereby an operator at the main exchange can signal the attendant operator over said trunk, a listening key at the attendant's position for answering the call, and a calling device connected in said trunk in readiness to operate said switch whenever said key is actuated.

22. In a telephone system, a manual main exchange and an automatic branch exchange, an attendant operator's position at the 60 branch exchange, a trunk line coming from the main exchange and extending through the attendant's position to an automatic switch at the branch exchange, means for signalling the attendant operator over said 65 trunk when a main to branch exchange connection is desired, a listening key at the attendant's position for answering the call, a calling device for operating said switch, and means whereby the actuation of said 70 key serves to connect the said calling device in the trunk so that the attendant can control said switch to complete the connection.

23. In a telephone system, a trunk line 75 connecting a manual exchange with an automatic exchange, a call signal at the manual end of said trunk, an automatic switch at the automatic end of said trunk, and separate controlling circuits for said signal and switch, each controlling circuit including 80 one conductor of said trunk line independent of the other.

24. In a telephone system, a two way 85 trunk line connecting a manual exchange with an automatic exchange, a call signal at the manual end and an automatic switch at the automatic end of said trunk, means for controlling said signal over a single talking conductor of said trunk in obtaining an 90 automatic to manual connection, and means for controlling said switch over the other talking conductor of said trunk independent of the first in obtaining a manual to automatic connection.

25. In a telephone system, a manual 95 exchange and an automatic exchange, a trunk line connecting the two and terminating in an automatic switch in the automatic exchange, means for connecting with said trunk at the manual exchange and for establishing a control circuit for said switch over one of the talking conductors of said 100 trunk independent of the other, a call signal for said trunk at the manual exchange, and means including another automatic switch 105 in the branch exchange for connecting with said trunk and for establishing a control circuit for said signal over the other talking conductor of said trunk independent of the first.

110 26. In a telephone system, main and branch exchanges, a trunk line connecting said exchanges and terminating in an automatic switch at the branch exchange, means for setting up a main to branch exchange 115 connection through the medium of said trunk line and switch, said means including means for establishing a control circuit for said switch over one conductor of said trunk line while maintaining the other conductor 120 125 130

free of battery connections at the branch exchange, and means for breaking said control circuit when the called subscriber answers and for locally controlling said connector thereafter, whereby both conductors of said trunk line are kept free from battery connections at the branch exchange during conversation.

27. In a telephone system, a manual main exchange and an automatic branch exchange, an attendant operator's switchboard at the branch exchange, a continuous two-way trunk line passing through said switchboard and connecting said exchanges, a jack 15 in which said trunk line terminates at the main exchange, progressively movable switches associated with said trunk line at the branch exchange, means including said trunk line, jack, and one of said switches 20 for completing main to branch exchange calls, and means including said trunk line, jack, and another one of said switches for completing branch to main exchange calls.

28. In a telephone system, a manual main exchange and an automatic branch exchange, an attendant operator's position at the branch exchange, a continuous trunk line connecting said exchanges and extending through said attendant's position, 25 means for establishing main to branch and branch to main exchange connections over said trunk line independent of the attendant operator, means for signalling the attendant over said trunk line when her assistance is desired by a subscriber in either exchange, and means whereby the attendant can answer when signalled and extend the required connection over said trunk line.

40 29. In a telephone system, two exchanges, means including an interoffice trunk line and an automatic switch in the second ex-

change for connecting a calling line in the first exchange with a called line in the second exchange, operator's equipment in the second exchange controlling the setting of 45 said switch, a supervisory relay in the first exchange, a relay in the second exchange controlling the circuit of said supervisory relay, a circuit for energizing said second 50 relay automatically responsive to an act of the operator incidental to handling the call, a locking circuit for said second relay, a relay in said switch controlled by the subscriber on the called line, and means controlled by said last mentioned relay for opening said locking circuit and for controlling the circuit of said supervisory relay after said second relay has deenergized.

30. In a telephone system, an interoffice 60 trunk line connecting two exchanges, means whereby an operator in the first exchange can signal an operator in the second exchange over said trunk line, a supervisory signal at the first exchange, a relay at the 65 second exchange initially energized by the operator at the second exchange when she answers the call, means whereby said relay controls said signal to give answering supervision to the first operator, automatic 70 switching mechanism controlled by the second operator for extending said trunk to a called line, a locking circuit for maintaining said relay energized after the second operator leaves the trunk upon completing the connection, and means controlled by the called subscriber on removing his receiver for opening said locking circuit and for maintaining the answered indication by said signal until the receiver is 75 replaced.

Signed by me at Chicago, Cook County, Illinois, this 14th day of April, 1920.

CLARENCE E. LOMAX.
